UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

DESIGN FOR A CASING FOR TELEPHONE TOLL APPARATUS.

SPECIFICATION forming part of Design No. 37,283, dated January 3, 1905.

Application filed February 6, 1904. Serial No. 192,472. Term of patent 7 years.

To all whom it may concern:

Be it known that I, GEORGE A. LONG, a citizen of the United States, and a resident of Hartford, in the county of Hartford and State of Connecticut, have invented a new, original, and ornamental Design for a Casing for Telephone Toll Apparatus, of which the following is a brief specification, reference being had to the accompanying drawing, forming a part thereof, and in which the figure is a perspec-

tive view showing the design of a casing for telephone toll apparatus.

What I claim is—

The ornamental design for casing for telephone toll apparatus, as shown.

GEORGE A. LONG.
